HOLDER FOR FISHING POLES AND RODS

Edwin M. Ammon, Kansas City, Mo. and
Howard J. Griffith, Shawnee, Kans.

Application May 17, 1954, Serial No. 30,537

Term of patent 3½ years

(Cl. D31—4)

Fig. 1.

Fig. 2.

Fig. 3.

Fig. 1 is an elevational view showing one edge of the holder for fishing poles and rods.

Fig. 2 is an elevational view showing the opposite edge thereof; and

Fig. 3 is a side elevational view of the holder for fishing poles and rods.

The fragmentary portion of a fish rod disclosed by means of broken lines in Fig. 3 is shown only for the purpose of illustration.

We claim:

The ornamental design for a holder for fishing poles and rods, as shown and described.
